Patented June 4, 1929.

1,715,467

UNITED STATES PATENT OFFICE.

JUAN OLIVERAS MODOLELL, OF BARCELONA, SPAIN.

CULTIVATOR.

Application filed October 17, 1927, Serial No. 226,764, and in Great Britain October 25, 1926.

This invention relates to cultivating machines generally known as horse hoes more particularly of the expanding kind formed by an approximately triangular frame with a vertex directed forward, the base of which is formed by curved concentric sectors which are adjustably secured to a central frame member of the machine, its sides forming the arms to which the sectors are pivoted and to which arms the lateral tool holders of the machine are mounted.

The invention consists in a cultivating machine of the above type wherein the said arms are provided at their free ends with a head of suitable form in each of which heads is pivotally mounted one of the said sectors which is guided in the head of the opposite arm.

Another feature of the machine is that it is so constructed that it may be pulled along by a single horse which is yoked to the machine by means of a pair of shafts which are pivotally attached to a forwardly projecting central beam of the machine so that no fore carriage is necessary, the depth of the cut or work of the machine being regulated by means of a screw adjustment between the said shafts and the said central beam of the machine.

Further features of the invention are hereinafter fully described and claimed in the appended claims.

The machine constructed in accordance with this invention has the advantage that the driver of the machine may release his hold on the handle and give the whole of his attention to leading the horse.

Provision is also made for it to be possible to change the tools of the machine so that the said machine can be employed in different and varied ways and is therefore of great use. Among other modes of employment may be mentioned the one in which it is employed as a plough or as a machine for hillling plants.

Moreover, as the two lateral tool carrying arms of the machine are independent of each other, they may be given each a different separation from the body of the machine, according to the requirements of the work to be done.

The machine is so constructed that the breadth of the machine may be reduced considerably without presenting any projections on its sides and in this way it can be employed for work between narrow lines of plants.

In the accompanying drawing is illustrated

a practical embodiment of the machine according to the invention.

Figure 1 is a side view of the machine.

Figure 2 is a plan view of the machine.

As shown in the drawing, this machine comprises a frame 1 of metal or other material and of suitable form, which at its front part comprises a forwardly projecting central beam 2 having a hole 20 for attachment of the draft means while at the back part of the machine is mounted the handle 3.

At the front part of the body 1 is disposed a tool carrying member 4 which is independent of the frame of the machine and which is attached to the frame at its upper part by means of a pin 5 of polygonal cross section, in order to prevent the rotation of the member, and at the lower part of the said member there is formed a recess 7 into which enters a projection 6 provided upon the frame 1.

The member 4, to which is attached the tool suited to the class of work which it is desired to do with the machine, is provided, at its upper part and on both sides of the frame 1, with lugs 8 in which by means of pins 9 are pivotally mounted the arms 10. Upon these arms are mounted at a suitable point the necessary tool carrying supports.

Each of the arms 10 forms, by means of its free end, a head 11 to which is pivotally joined a sector 12 and the said sectors, which are concentrically superposed on each other, are guided in the head of the opposite arm to the one to which they are jointed and at the same time in a clamp 13 by means of which they are fixed through the medium of a screw 14.

The clamp 13 forms a member which comprises, in addition, a back plate 15 and the lateral arms or guide brackets 16 for receiving the sectors 12, the lower support 17, secured to the frame 1, and an extension 18 on which is mounted in a desired manner a suitable tool holder.

Moreover, the said member is strengthened by means of stays 19.

As the sectors 12 and the arms 10 are independent of each other sectors of different length may be employed in this way, and in no case, however small be the width of the machine, will the free ends of the sectors project from the sides of the same, since in each case they will be employed of a suitable length or else they may be jointed and turned back on both sides of the machine.

With a view to making this machine trans-

formable, in order to facilitate handling of it and the changing of the necessary parts in each case, the nuts of the bolts by means of which its component parts are connected together are of the wing nut type which can be manipulated without necessitating the use of spanners or other tools.

In order to employ the machine as a plough, the parts 4 and 10 are detached, together with 10 the sectors and clamp 13 and ploughing tools are attached to the frame 1.

The machine described may be modified as regards its dimensions and the shapes of its accessory parts, details of construction of its 15 component parts, and the materials of which the same are made, without on that account changing, altering or modifying the essential nature of the same.

Having now described my invention, what 20 I claim as new and desire to secure by Letters Patent is:—

1. An expanding cultivating machine of the kind formed by an approximately triangular frame with a vertex directed forward 25 the base of which is formed by curved concentric sectors which are adjustably secured to a central frame member of the machine, its sides forming the lateral arms to which the sectors are pivoted and in which arms the 30 lateral tool holders of the machine are mounted, wherein the said arms are provided at their free ends with a head of suitable form in each of which heads is pivotally mounted one of the said sectors which is guided in the 35 head of the opposite arm.

2. A cultivating machine according to claim 1, wherein the lateral arms are pivotally mounted on, and a forward tool is secured to a front member which is detachably 40 secured to the frame of the machine, to which said front member is secured at its upper part by means of a pin of polygonal cross section while at its lower part there is formed a recess into which enters a projection provided 45 upon the frame proper.

3. An expanding cultivating machine of the kind formed by an approximately triangular frame with a vertex directed forward, the base of which is formed by curved con-

centric sectors which are adjustably secured 50 to a central frame member, its sides forming the lateral arms to which the sectors are pivoted and on which arms the lateral tool holders of the machine are mounted, comprising a head on the free ends of each of said arms, 55 a sector pivotally mounted in each of said heads, which heads are adapted to guide the sector of the opposite head, a front member detachably secured at the upper part, by means of a pin of polygonal cross-section to 60 the frame of the machine upon which front member the lateral arms are pivoted and upon which a forward tool is secured, while at the lower part of the said front member a recess is provided which is adapted to receive 65 a projection provided upon the frame, a detachable combined guide bracket and clamp for the sectors, said guide bracket consisting of a back plate, two lateral brackets for said sectors, one central bracket in which 70 the sectors are fixed by means of a screw, means for securing the said guide bracket to the frame and a projection adapted to receive a tool holder to the rear of said guide bracket. 75

4. An expanding cultivating machine of the kind formed by an approximately triangular frame with a vertex directed forward, the base of which is formed by curved concentric sectors which are adjustably secured 80 to a central frame member, its sides forming the lateral arms to which the sectors are pivoted and on which arms the lateral tool holders of the machine are mounted, comprising a head on the free ends of each of said arms, 85 a sector pivotally mounted in each of said heads, which heads are adapted to guide the sector of the opposite head, a detachably combined guide bracket and clamp for the sectors, said guide bracket consisting of a 90 back-plate, two lateral brackets for said sectors, means for securing said guide bracket to the frame and a projection adapted to receive a tool holder to the rear of said guide bracket. 95

In testimony whereof I have signed my name to this specification.

JUAN OLIVERAS MODOLELL.
